UNITED STATES PATENT OFFICE

2,030,783

GUARD DEVICE

John P. Dennebaum, Scranton, Pa.

Application September 5, 1935, Serial No. 39,331

9 Claims. (Cl. 256—13.1)

This invention relates to a guard device for protective purposes on highways and is designed primarily for positioning at the sides of a curve of a roadway; however, it is to be understood that a guard device, in accordance with this invention, may be employed at any point upon the roadway or in any connection for which it may be found applicable.

The invention has for its further object to provide, in a manner as hereinafter set forth, a guard device including a resilient structure for clamping and suspending a guard rail and with the structure having oppositely disposed inherent parts for clamping the rail thereto.

The invention has for its further object to provide, in a manner as hereinafter set forth, a guard device constituting a cushioned abutment for arresting a vehicle from passing off a roadway sidewise, more particularly when rounding curves, thereby reducing possibilities of accidents to a minimum.

A further object of the invention is to provide, in a manner as hereinafter set forth, a guard device including means for absorbing shocks, as well as reducing to a minimum damage or injury to a vehicle when the latter impacts the device.

A further object of the invention is to provide, in a manner as hereinafter set forth, means for resiliently supporting a roadway guard-rail at its ends and at spaced points intermediate its ends.

A further object of the invention is to provide, in a manner as hereinafter set forth, a guard device including a resilient suspension means having oppositely disposed parts for overlapping the lengthwise edges of a guard rail for clamping the latter to and in abutting relation with respect to the body of said means.

A further object of the invention is to provide, in a manner as hereinafter set forth, a guard device including a resilient suspension means having parts thereof for clamping a guard rail section thereagainst without perforating the rail.

A further object of the invention is to provide, in a manner as hereinafter set forth, a guard device for the purpose referred to including a sectional guard rail and resilient suspensions for the rail, and with each suspension having oppositely disposed spaced parallel channels at its front for receiving a guard rail section to couple the latter to the suspension.

Further objects of the invention are to provide, in a manner as hereinafter set forth, a guard device for the purpose referred to which is simple

in its construction and arrangement, strong, durable, thoroughly efficient in its use, readily installed in position upon a roadway and comparatively inexpensive to manufacture.

With the foregoing and other objects which may hereinafter appear, the invention consists of the novel construction, combination and arrangement of parts, as will be more specifically described and illustrated in the accompanying drawing, wherein is shown an embodiment of the invention, but it is to be understood that changes, variations and modifications may be resorted to which fall within the scope of the invention as claimed.

In the drawing:

Figure 1 is a fragmentary view in front elevation of the device.

Figure 2 is a fragmentary view in top plan of the device.

Figure 3 is a side elevation of the form of suspension element employed, anchored against the front of a vertical support.

Figure 4 is a perspective view of the form of suspension element.

Figure 5 is a view similar to Figure 3 showing the assembling of a guard rail relative to a combined clamp and suspension element, and

Figure 6 is a vertical sectional view of a modified form of guard device in accordance with this invention.

The guard device includes a plurality of side-wise aligned spaced intermediate posts 10 and a pair of end posts 11 (only one shown) spaced laterally from the posts 10. Each post 10 is of like form and is formed of a body 13, preferably wood, having flat side faces 14, a flat front face 15 and a flat rear face 16. The top 17 of the body 13 inclines downwardly from front to rear. The posts 10, in proximity to their upper ends, are formed with openings 18 which extend from the front to the rear faces thereof. The posts 10 have their lower portions anchored in the ground adjacent to the side of a roadway. The posts 11 also are to have their lower portions anchored in the ground 19, but are to extend a greater distance above the ground than the posts 10.

The guard device also includes a bow-shaped metallic guard rail 20 formed of a plurality of intermediate sections 27 and a pair of end sections 28. Only one end section 28 is shown. The guard rail sections 27 are of like form, of rectangular contour, of the desired length and width and each is disposed on its lower lengthwise edge. The sections 27 are arranged in overlapping relation, as indicated at 30. The overlapped portions 35

of the sections 27 are anchored together in abutting engagement by the spaced holdfast means 31.

Positioned against the inner face of an end section is a one-piece angle-shaped element 32, which provides a reinforcement for an end of the guard rail. The element 32 also provides a connector and abutment for a resilient coupling and suspension structure 72^a for the guard rail.

The guard device also includes extendible and contractible open front resilient combined guard rail clamping and suspension elements 45 of like form and which correspond in number to the number of posts 10. Each element 45 is anchored against the front of a post 10. The elements 45 are of like form and each is constructed of a resilient metallic strap of the desired gauge bent to form a vertically disposed rear part 46, terminating at its ends into a pair of oppositely disposed spaced upper and lower segmental inner coupling parts 47, 48, which merge respectively into a pair of spaced oppositely extending endwise aligned vertically disposed intermediate parts 49, 50 merging respectively at their aligning ends into a pair of spaced oppositely disposed upper and lower segmental outer coupling parts 51, 52, terminating respectively into a pair of spaced vertically extending oppositely disposed endwise aligning front parts 53, 54, which merge respectively into a pair of vertically extending oppositely disposed outwardly arranged clamping jaws 55, 56. The jaws, in connection with the parts 53, 54, provide oppositely disposed upper and lower channels or grooves 57, 58 respectively to receive a guard rail or a guard rail section. The part 53 extends above the inner coupling 47. The part 54 depends below the inner coupling part 48. The rear part 46, centrally thereof, is formed with an opening 59. The parts 49, 50 oppose and are spaced from part 56 by the parts 47, 48. The parts 53, 54 oppose and are spaced from the parts 49, 50 by the parts 51, 52. The parts 47, 48 are of greater length than the parts 51, 52. The jaws 55, 56 are of semi-circular contour.

The part 46 is positioned against the front face of a post 10 and with its opening 59 registering with opening 18. Extending through the registering openings 18, 59 is a threaded bolt 60 having a head 61 and carrying washers 62, 63 and a clamping nut 64. The washer 62 is interposed between part 46 and bolt head 61. The washer 63 is interposed between nut 64 and the rear face 16 of post 10. The bolt 60, washers 62, 63 and nut 64 coat with the post 10 and part 46 for anchoring element 45 to the post.

There is associated with each post 11 a bracing means 65 therefor which is to be anchored in the ground.

When the guard rail is to be resiliently suspended, the bottom of the rail is placed in the lower channel 58 of element 45 and the top jaw 55 of such element is then sprung into place by any suitable tool for the purpose of having the top of the rail seat or extend into the upper channel 57 of element 45 whereby the rail will be clamped to element 45 and resiliently suspended relative to a post 10. Preferably the guard rail will be formed of the intermediate sections 27 and a pair of end sections 28. Only one end section is shown. One of the sections 27 will be connected to one of the elements 45 in the manner as referred to and after which another section 27 will be connected to an adjacent element 45 in a manner as referred to, but with an end of the second connected section 27 overlapping an end of the first connected section 27.

The overlapping ends of such sections 27 will then be connected together by the hold-fast means 31. After the desired number of the sections 27 are clamped to the elements 45, an end section 28 is secured to an outer end portion of an outer section 27. When section 28 has been secured to section 27, the section 28 is resiliently and slidably connected to a post 11 by the structure 72^a.

With reference to the modified form of guard device shown in Figure 6. It will be of the same construction as that shown in Figure 1 with the exception that a pair of superposed guard rails and two sets of superposed extendible and contractible open front resilient guard rail clamping and suspension elements are employed. In Figure 6 an intermediate post is designated 89 and it is formed with a pair of superposed openings 90, 91. Extending through the openings 90, 91 are anchoring means 92, 93. Secured to the front of the post 89 by the holdfast means 92, 93 are the upper and lower combined clamping and suspension elements 94, 95 respectively for the guard rails 96, 97 respectively. Each holdfast means corresponds to the headed bolt 60, washers 62, 63 and nut 64. The combined guard rail 25 clamping and suspension elements 94, 95 are of like form and correspond in structure to that of the elements 45. The guard rails 96, 97 are of the same form as the guard rail 26. The end posts 11, the bracing means 65 for the end posts 30 and the resilient structures 72^a will be employed in the form shown in Figure 6.

What I claim is:

1. In a guard device, an extendible and contractible open front and closed rear guard rail clamping and suspension element having oppositely disposed superposed spaced clamping jaws at its front for clamping the rail against said element, said element having parts coacting with said jaws to provide upper and lower oppositely disposed spaced aligning channels for receiving respectively the top and bottom of the rail.

2. In a guard device, an extendible and contractible guard rail clamping and suspension element consisting of a resilient strap like body formed of a vertical rear part terminating at its ends into a pair of oppositely disposed superposed spaced upper and lower inner coupling parts merging into a pair of oppositely extending superposed spaced upper and lower vertically disposed intermediate parts, said intermediate parts terminating into a pair of oppositely disposed superposed spaced upper and lower outer coupling parts merging into a pair of oppositely extending superposed spaced upper and lower front parts terminating into a pair of vertically extending oppositely disposed superposed spaced rail clamping jaws.

3. In a guard device, an extendible and contractible guard rail clamping and suspension element consisting of a resilient strap like body formed of a vertical rear part terminating at its ends into a pair of oppositely disposed superposed spaced upper and lower inner coupling parts merging into a pair of oppositely extending superposed spaced upper and lower vertically disposed intermediate parts, said intermediate parts terminating into a pair of oppositely disposed superposed spaced upper and lower outer coupling parts terminating into a pair of oppositely extending superposed spaced upper and lower front parts terminating into a pair of vertically extending oppositely disposed superposed spaced rail clamping jaws, said jaws in connection with said front

parts providing a pair of oppositely disposed superposed spaced channels.

4. In a guard device, an extendible and contractible guard rail clamping and suspension element consisting of a resilient strap like body formed of a vertical rear part terminating at its ends into a pair of oppositely disposed superposed spaced upper and lower inner coupling parts merging into a pair of oppositely extending superposed spaced upper and lower vertically disposed intermediate parts, said intermediate parts terminating into a pair of oppositely disposed superposed spaced upper and lower outer coupling parts merging into a pair of oppositely extending superposed spaced upper and lower front parts terminating into a pair of vertically extending oppositely disposed superposed spaced rail clamping jaws, said front parts extending above and depending below respectively the said upper and lower inner coupling parts.

5. In a guard device, an extendible and contractible guard rail clamping and suspension element consisting of a resilient strap like body formed of a vertical rear part terminating at its ends into a pair of oppositely disposed superposed spaced upper and lower inner coupling parts merging into a pair of oppositely extending superposed spaced upper and lower vertically disposed intermediate parts, said intermediate parts terminating into a pair of oppositely disposed superposed spaced upper and lower outer coupling parts merging into a pair of oppositely extending superposed spaced upper and lower front parts terminating into a pair of vertically extending oppositely disposed superposed spaced rail clamping jaws, said front parts extending above and depending below respectively the said upper and lower inner coupling parts.

6. In a guard device, an extendible and contractible guard rail clamping and suspension element consisting of a resilient strap like body formed of a vertical rear part terminating at its ends into a pair of oppositely disposed superposed spaced upper and lower inner coupling

parts merging into a pair of oppositely extending superposed spaced upper and lower vertically disposed intermediate parts, said intermediate parts terminating into a pair of oppositely disposed superposed spaced upper and lower outer coupling parts merging into a pair of oppositely extending superposed spaced upper and lower front parts terminating into a pair of vertically extending oppositely disposed superposed spaced rail clamping jaws, said jaws in connection with 10 said front parts providing a pair of oppositely disposed superposed spaced channels, and said rear part formed with an opening adapted for the passage of a holdfast means to anchor the element against a post.

7. In a guard device, a pair of end posts, a set of intermediate posts arranged between the end posts, a guard rail arranged outwardly adjacent said intermediate posts, a guard rail clamping and suspension element anchored to the front 20 of each intermediate post in laterally extended relation to the latter, each of said elements having an extendible and contractible open front provided with oppositely disposed spaced channels for receiving the guard rail and oppositely 25 disposed spaced jaws for clamping the rail in said channels, and means for resiliently and slidably connecting the ends of the guard rail to the end posts.

8. In a guard device, a guard rail, and resilient 30 suspension elements for said rail, each of said elements including an open front provided with spaced means for receiving the top and bottom of the rail and possessing a snapping characteristic for clamping the rail in said open front to 35 resiliently suspend the latter.

9. In a guard device, a guard rail, and resilient suspension elements for said rail, each of said elements including an open front provided with spaced means for receiving the top and bottom 40 of the rail and possessing a snapping characteristic for clamping the rail in said open front to resiliently suspend the latter, the said means including a pair of oppositely disposed spaced channels and a pair of oppositely disposed spaced 45 clamping jaws.

JOHN P. DENNEBAUM.
